UNITED STATES PATENT OFFICE.

FERDINAND GIRARD, OF PARIS, FRANCE.

CIGARETTE-MACHINE.

SPECIFICATION forming part of Letters Patent No. 586,599, dated July 20, 1897.

Application filed May 16, 1895. Serial No. 549,533. (No model.) Patented in Switzerland January 29, 1894, No. 8,034; in France June 23, 1894, No. 239,282, and in England May 16, 1895, No. 9,718.

To all whom it may concern:

Be it known that I, FERDINAND GIRARD, a citizen of the Republic of France, and a resident of Paris, France, have invented certain new and useful Improvements in Cigarette-Machines, (for which I have obtained patents in France June 23, 1894, No. 239,282; in Switzerland January 29, 1894, No. 8,034, and in England May 16, 1895, No. 9,718,) of which the following is a specification.

My invention relates to improvements in cigarette-machines, and has for its object to increase the capacity of such machines.

My improved machine is constructed to automatically perform the following operations, to wit: feeding the paper from rolls, distributing the proper quantity of tobacco, molding the tobacco, wrapping the paper around the tobacco, closing the ends, and discharging the finished cigarettes.

The construction and operation of my machine will best be understood when described in connection with the accompanying drawings, in which—

Figure 1 represents an end view of a machine constructed according to my invention. Fig. 2 is a side view, partly in section, on the line 2 2, Fig. 1. Fig. 3 is a cross-section on the line 3 3, Fig. 1. Fig. 4 is an end view of the left-hand lower part of the machine. Fig. 5 is a view of the right-hand lower part. Figs. 6 to 23 are detail views.

Similar numerals and letters of reference designate like parts throughout the several views of the drawings.

The frame of the machine is composed of superposed parts 1, 2, and 3, supporting the hopper 4. Upon the front part of the frame 1 are located two supports 5 and 6, and upon the rear part of the same is mounted the main shaft *a*, carrying cams 7, 8, 9, 10, 11, 12, 13, and 14, which actuate the different parts of the machine.

I will now proceed to describe the several parts in the order of their operations.

The paper-feed.—The roll of paper *b* of a width equal to the length required for a cigarette is suspended upon the shaft of the yoke-shaped bracket 15, secured to the front part 50 of the hopper 4. The paper passes down in

front, then partly around the feed-roll 16 and between the rolls 17 and 18, which coöperate to feed the width of paper required for a cigarette. The feed-roll 17 is keyed upon a shaft turned by a ratchet-wheel actuated in one direction by a sector on a vibrating bell-crank lever 19, carrying a roller which engages the groove of the cam 10 on the main shaft *a*. In front of the feed-rolls for the paper is placed a paper-cutting apparatus consisting of two knives 20 and 21, the knife 20 being fixed, while the knife 21 is vibrated on a shaft 22 by means of a rod 23 and a bell-crank lever 24, actuated by a cam 13.

Distribution.—The system of distribution 65 is based upon the use of a rotating measuring-cup *c*, fixed upon an arm 25, keyed upon a shaft *d*, supported in the upper frame 3 and actuated by a dog 26, fixed upon the hub of a gear-wheel 28, the dog 26 engaging a notch 70 in a small crank-disk 27, fixed on the shaft *d*. From the disk 27 motion is also imparted to a tobacco-agitator *A*, located within the hopper 4, by a connecting-rod, ratchet, and bevel-gear mechanism *e f g*, acting on a shaft to 75 which said agitator is secured. The gear-wheel 28 receives motion from the main shaft *a* through the toothed cam-wheel 10 and intermediate wheel 29. The object of the use of the dog 26 is to be able by raising it to entirely stop the operation of the apparatus for distributing and agitating the tobacco. The cup *c* is placed into a receiving-chamber communicating with and receiving the tobacco from the hopper 4. At each revolution of the 85 cup said cup fills with tobacco while passing through the latter and discharges the tobacco so received on the first quadrant of its downward stroke.

In front of the vertical line passing through 90 the axis of rotation of the cup *c* is located a series of receivers 30. (Shown on a larger scale in Figs. 6 and 7.) Said receivers receive the tobacco thrown forward by the cup upon the edge 31, divide the charge into two 95 parts which pass through the tubes 32 to the box 33 of the small frame 34, which forms a distributing-chamber, where the tobacco is evenly spread. Through this chamber passes a discharger 35, fixed to the end of a rod 83, 100

guided within the frame 34 and connected to a groove of the toothed wheel 28 through levers 36. The object of this discharger is to rapidly push the tobacco into the vertical chamber B of the mold.

Molding.—The molding apparatus must, during the formation of the cigarette, have a perfectly-cylindrical cavity, but must, for the operation of distribution and discharge, be open at certain times. For this reason the apparatus must be composed of several movable parts converging toward the axis when the cigarette is formed, for which purpose I have adopted the arrangement shown on a larger scale in Figs. 8, 9, 13, and 14. In front of the frame 34 is fixed a plate 38, notched to fit the chamber 33 and extending downward to the level of the axis of the closed mold. In front of this, held at a distance equal to the diameter of the cigarette by plates 39, is secured another plate 40, the whole forming a plunger-box. Into the vertical chamber formed by this plunger-box the active member or plunger 41 of the mold passes. It is secured to a holder 42, guided within the forward part of the frame 3, and operated by the bell-crank lever 43, the roller of which engages a groove of the cam 11 on the main shaft *a*.

As the cigarette must be discharged at the bottom, I have made the lower half of the mold in two sections or jaws 44 and 45, which are moved away to make room for the discharge. This removal of the lower parts of the mold may be effected in various ways, but I shall here describe only the one adopted by me.

The inner jaw 44 of the lower mold is fixed to the vertical slide 46, and the outer jaw 45 is fixed to the horizontal carriage 47 in such a way that at the time of discharge the parts 41, 44, and 45 occupy the positions indicated by dotted lines in Fig. 8.

The two jaws 44 and 45 are actuated by the same mechanism, consisting of a forked lever 48, the roller of which engages a groove of the cam-disk 12. It vibrates on the shaft 49. A bell-crank lever 50, connected to a link at the left-hand end, Fig. 3, of this lever, actuates the sliding carriage 47 with the jaw 45, and a shaft 51 connects the vertical support 46 to the forked lever in such a manner that when the jaw 44 is depressed the jaw 45 moves out, and conversely.

A lever 52, vibrating in the frame 34, is operated by the face of the cam 12. Its outer end is forked, the prongs 53 closing the ends of the cavity in the plunger the moment tobacco is thrown upon the paper. Between the prongs and behind the plate 38 is fixed the blast-nozzle 54, connected with the air-compressor 84, actuated by cam 14, as shown in Fig. 5.

Wrapping.—The wrapping apparatus (shown in Fig. 1 and part of it on a larger scale in Fig. 10 and Figs. 15 to 22) is arranged symmetrically in the line of the axis of the

mold. It has on the right a cylinder 55, free to turn within the standard 5, but fixed longitudinally. This cylinder has gear-teeth at its inner end and is tubular in form to receive a spindle 56, consisting of a steel tube, which is provided with a groove containing a washer held by a bolt screwed through the cylinder 55, so that the spindle is connected to the latter as to rotary motion, but capable of independent longitudinal motion imparted to it by a forked lever 58, engaging groove of cam 8. Rotation is caused by the sector 59, Figs. 1 and 4, keyed to the intermediate shaft 80 60 and gearing into the teeth at the end of the cylinder 55, the whole being actuated by cam 9 and arm 61, Fig. 1. The wrapping device or bayonet 62 consists of a thin blade of curved cross-section, Fig. 11, secured to the end of the spindle 56 in the following manner: The bore of the end of the spindle 56 is enlarged to the internal diameter of the bayonet, split by a saw cut, and provided internally with a cone-thread to receive the threaded end of the bayonet, a sleeve over the end of the bayonet inclosing the whole joint, the screwing of the end of the bayonet into the split end of the spindle forcing the latter against the inner surface of the sleeve. A set-screw prevents all accidental displacement.

The second part of the wrapping apparatus at the right side, Figs. 1 and 10, consists of a cylinder 55^b, toothed like the cylinder 55 and turning in the standard 6, but not perforated. Rotary movement is imparted to it through the sector 64, keyed upon the intermediate shaft 60, so connected that the two cylinders 55 and 55^b move exactly alike. The inner end of the cylinder 55^b is recessed for the reception of a pin 65, which leaves a space for the reception of the end of the bayonet.

A rod 66 slides within the tubular spindle 55, its end being provided with a piston 82, the object of which is to guard against the cigarette following the bayonet when withdrawn. This rod 66 is connected to a counter-rod 67, Fig. 1, by an arm 68 and actuated by cam 7 and lever 69.

Folding.—The closing of the ends of the cigarette is effected by two organs acting one after the other, the first of which I call "folders" and the latter "fingers."

The folder mechanism consists of two vertical sliding rods 70, Fig. 1, connected by a cross-head 71, into the end of which engages a lever 72, Figs. 1 and 2, receiving motion from the cam 73. These rods 70 are only the intermediate organs for transmitting motion. The folders proper, 74, (shown on a larger scale in Fig. 9 and Figs. 19 to 22,) are mounted on the front part of the frame 34 and on both sides of the mold-channel. Their operative ends are dressed to a special, and they have curved slots engaged by fixed guide-pins 75 and 76. The folders are connected to the sliding rods 70 by links 77. On the spindle 56 there is a stop 78, Fig. 2, secured to the

sliding rod 70, its object being to slightly deflect the bayonet when entering the mold to prevent the latter butting against the counter-mold.

5 The finger mechanism consists of two horizontal arbors turning in horizontal bearings on the mold-support 46. The axis of rotation of these two arbors is a little lower down than the tangent passing through the bottom of 10 the counter-mold 44, so as to force the paper into the openings formed at the ends of the latter when closed, Figs. 19 to 22. Upon the 15 cord of the arbors (on the side of the counter-mold) are fixed the finger-holders, opposite thereto two conical pinions, to which motion is imparted from two sectors fixed laterally upon shaft 79, Figs. 2 and 3, actuated by cam 13 and an arm with a roll likewise upon shaft 79 and engaging cam 13. 20 When the mold-holder 46 descends, the fingers bear against the sectors and through the pinions make one revolution, which assists the discharge of the cigarette.

Operation. — The hopper being charged 25 with tobacco and the paper-roll in place, the paper is passed between the feed-rolls. The machine is then operated to open the counter-mold, the plunger rising again, but not yet uncovering the bottom of the distributing-chamber, the prongs lowered, the paper advances sufficiently for one cigarette, the counter-mold closes, the plunger rises to the end of the stroke, while the bayonet enters the opposite cylinder. The discharger then 30 rapidly pushes the tobacco into the vertical channel and causes it to fall upon the paper. The plunger redescends and compresses the tobacco. At this instant the shears cut the paper, while the prongs rise to completely 35 uncover the ends of the mold. The bayonet then makes its rotation, wrapping the paper around the tobacco, and the central rod advances to permit the withdrawal of the bayonet by holding the cigarette in the mold. 40 Toward the end of the movement of the bayonet the central rod recedes to make room for the folders, which descend to make the first fold and recede at once, while the fingers turn the folds in and at once resume their 45 former positions. The wrapping of the cigarette is more clearly illustrated in Figs. 15 to 18. The paper, as shown in Fig. 15, is fed forward sufficiently to overlap a portion of one side of the mold, while the bayonet enters beneath the paper and lies against one wall of the counter-mold. After the tobacco 50 is compressed in the mold, as shown in Fig. 16, the bayonet rotates in the direction shown by the arrow in Fig. 17. At the commencement of said rotation the edge of the paper is caused to fold over the bayonet, as shown in Fig. 17, and the paper is then carried with the bayonet. The revolution of the bayonet continues until it reaches the position shown 55 in Fig. 18. The plunger then abuts against the tobacco and the bayonet is withdrawn, leaving the cigarette rolled and its ends free

from tobacco for a short distance to permit the same to be closed up. The folders 74 now descend and turn a portion of each end 70 downwardly and inwardly, and then rise again. The fingers 74^a, made tapering and triangular in cross-section, turn in the direction of arrow 7, Fig. 19, and turn the lower half of the paper upwardly and inwardly, as 75 shown in Fig. 21. The counter-mold opens then while the air-compressor discharges a strong jet of air upon the finished cigarette and throws it out. As soon as the plunger in its descent has cleared the bottom of the 80 distributing-chamber the discharger recedes to allow the tobacco projected by the cup to fall down for the next cigarette.

What I claim as new is —

1. In a cigarette-machine, the combination 85 with a receiving-chamber for the tobacco, a distributing-chamber and a molding mechanism, of a rotary distributing-cup arranged within the receiving-chamber and adapted to take up the tobacco and to discharge the same 90 in measured quantities, and means for conducting the tobacco discharged from the distributing-cup to the molding mechanism, substantially as described.

2. In a cigarette-machine, the combination 95 of a receiving-chamber for the tobacco, a molding mechanism, a rotary distributing-cup located within the receiving-chamber, a series of receiving-tubes adapted to receive and divide the charge delivered thereto by the distributing-cup, and means for conducting the charge delivered by the receiving-tubes to the molding mechanism, substantially as described.

3. In a cigarette-machine, the combination 105 of a receiving-chamber for the tobacco, a molding mechanism, a rotary distributing-cup located within the receiving-chamber, a series of receiving-tubes adapted to receive and divide the charge delivered thereto by the distributing-cup, a distributing-chamber communicating with the receiving-tubes, and a discharger within the distributing-chamber for discharging the charge from the distributing-chamber to the mold, substantially as de- 110 115 scribed.

4. In a cigarette-machine, the combination 120 of a plunger-box, a mold comprising two separable sections, a plunger co-operating with the same to mold the charge and mounted to reciprocate in said plunger-box, a distributing-chamber in communication with the plunger-box, means for conducting a measured charge to the distributing-chamber, a dis- 125 charger operating in the distributing-chamber and operated for delivering the charge into the plunger-box when the plunger is raised, and means for operating the several parts, substantially as described.

5. In a cigarette-machine, the combination 130 of a mold comprising two separable sections, a plunger co-operating with the same to mold the charge and mounted to reciprocate, a plunger-box, a lateral distributing-chamber in

communication with the plunger-box, means for conducting a measured charge to the distributing-chamber, a reciprocating discharger operating within the distributing-chamber to discharge the charge into the plunger-box when the plunger is raised, and means for operating the several parts, substantially as described.

6. In a cigarette-machine, the combination of a mold comprising two separable sections, a plunger-box above the mold-sections, a plunger mounted to reciprocate within the box and coöperating with the mold-sections, and a pronged lever having its prongs embracing the plunger-box and actuated to laterally close the plunger-cavity after the tobacco is thrown upon the paper, substantially as described.

7. In a cigarette-machine, the combination of a mold composed of two separable sections, a plunger-box arranged adjacent to the mold-sections, a plunger mounted to reciprocate in said box and coöperating with the mold-sections to mold the cigarette, a horizontal carriage supporting one of the mold-sections and adapted to move toward and from the plunger-box, a vertical carriage supporting the second mold-section, a cam, and a lever actuated by said cam and placed in operative connection with the carriage and slide, substantially as described.

8. In a cigarette-machine, the combination of a mold composed of two separable sections, a plunger-box arranged adjacent to the mold-sections, a plunger mounted to reciprocate in said box and coöperating with the mold-sections to mold the cigarette, a horizontal carriage supporting one of the mold-sections and adapted to move toward and from the plunger-box, a vertical carriage supporting the second mold-section, a cam, a lever actuated by said cam and placed in operative connection with the carriage and slide, and an air-blast apparatus for directing a jet of air upon the cigarette to effect its discharge from the mold when the mold-sections are separated, substantially as described.

9. In a cigarette-machine, the combination of a mold, two rotary heads arranged on opposite sides of the mold in line with the cavity thereof, a bayonet carried by one of said heads and movable longitudinally with respect to the same, and a jaw in the opposite head adapted to receive the free end of the

bayonet to coöperate in rotating the same, substantially as described.

10. In a cigarette-machine, the combination of a mold, two rotary heads arranged on opposite sides of the mold in line with the cavity thereof, a bayonet carried by one of said heads and movable longitudinally with respect to the same, a jaw in the opposite head adapted to receive the free end of the bayonet to coöperate in rotating the same, and a reciprocating rod adapted to engage with the end of the cigarette on the withdrawal of the bayonet, substantially as described.

11. In a cigarette-machine, the combination of a hopper, a receiving-chamber in communication with the same, a rotary distributing-cup located within the receiver, a distributing-chamber, a tube adapted to receive the charge from the cup and communicating with the receiving-chamber, a vertical channel communicating with the distributing-chamber, a mold in communication with said chamber, a feed for conveying the paper to the mold, a paper-severing mechanism, means for folding in the ends of the cigarette, and a discharger for conveying the charge from the distributing-chamber to the vertical chamber, substantially as described.

12. In a cigarette-machine, the combination of the hopper 4, a receiving-chamber, a rotatable measuring-cup *c* located in the receiving-chamber, the distributing-chamber 33, a tube or tubes 32 adapted to receive the charge from the measuring-cup and communicating with the distributing-chamber, a plunger-box vertically placed and communicating with the distributing-chamber, a reciprocating plunger 41 in said plunger-box, a discharger 35 adapted to push the charge into the plunger-box when the plunger is in its upper position, separable mold-sections 44 and 45, a feed and severing device for the paper, a bayonet 62, end-folders, and operative connections, substantially as shown and described.

In witness whereof I have hereunto signed my name in the presence of two subscribing witnesses.

FERDINAND GIRARD.
